United States Patent

Des. 235,949
Patented July 22, 1975

235,949

SUPPORT FOR TENNIS RACKET AND RELATED ARTICLES

William J. Garvey, Rte. 1, Indian Trail Road,
Barrington, Ill. 60010

Filed Nov. 23, 1973, Ser. No. 418,672

Term of patent 14 years

Int. Cl. D6—04

U.S. CL. D6—85

FIG. 1 is a left front perspective view of a support for tennis racket, and related articles, showing my new design;

FIG. 2 is a front view thereof;

FIG. 3 is a left side view thereof, the right side view being substantially a mirror image thereof;

FIG. 4 is a bottom view thereof;

FIG. 5 is a top view thereof; and

FIG. 6 is a rear view thereof.

I claim:

The ornamental design for a support for tennis racket and related articles, substantially as shown and described.
